UNITED STATES PATENT OFFICE.

ROBERT SORGAN, OF JERSEY CITY, NEW JERSEY.

CLOSURE FOR BOTTLES, JARS, AND SIMILAR RECEPTACLES.

Application filed July 17, 1923. Serial No. 652,022.

To all whom it may concern:

Be it known that I, ROBERT SORGAN, a citizen of the United States, and a resident of Jersey City, county of Hudson, and State 5 of New Jersey, have invented certain new and useful Improvements in Closures for Bottles, Jars, and Similar Receptacles, of which the following is a specification.

This invention relates to closures for bottles, jars and similar receptacles and has for its primary object to provide a closure which can be easily and quickly applied to tightly seal the mouth of the bottle or jar, affording a complete protection to the contents thereof and which, after it is once applied, cannot be removed and then replaced without detection.

It is a further object of my present improvements to provide a bottle or jar closure 20 of the above character which may be inexpensively made from sheet metal, and can be readily constructed in various sizes for application to bottles, jars or other receptacles of numerous shapes or forms.

With the above and other objects in view, the invention resides in the improved receptacle closure and in the form, construction and relative arrangement of the several parts as may be hereinafter more fully described, illustrated in the accompanying drawings and subsequently incorporated in the subjoined claims.

In the drawings wherein I have illustrated one practical and satisfactory embodiment of the invention and in which similar reference characters designate corresponding parts throughout the several views:

Figure 1 is a side elevation of a portion 40 of a bottle or jar provided with my new closure;

Figure 2 is a vertical sectional view thereof on an enlarged scale;

Figures 3 and 4 are views similar to Figures 1 and 2 showing a slightly modified embodiment of the invention;

Figure 5 is a horizontal section taken on the line 5—5 of Figure 2; and,

Figure 6 is a sectional view showing the initial form of another type of the closure cap.

In the accompanying drawing for purposes of illustration, I have shown the closure device as applied to a bottle or jar of cylindrical form though it will be understood as the description proceeds that the

device is also applicable to receptacles of other shapes and constructed of glass or other materials. For the purposes of this description, it will suffice to state that the 60 body 5 of the bottle or receptacle is provided at its upper end with the usual contracted neck 6, the mouth 7 on the upper end of said neck being provided with an external annular shoulder 8.

The improved closure consists of a sheet metal cap 9 formed by a suitable stamping operation to provide a marginal flange or rim 10 extending at right angles to the plane of the body wall of said cap. Against the inner face of this body wall within the rim or flange 10, a disc of cork, cardboard, or other compressible material 11 is arranged, and the lower face of this disc is covered by a sheet of paper 12 which is glazed, paraffined, or otherwise rendered moisture resistant or impervious.

Adjacent to the rim 10 of the bottle cap, the body wall thereof is provided with an annular indentation 13, said indentation being formed in a suitable machine which also produces an annular rib or bead 14 on the lower face of the disc 11 and paper sheet 12. When the cap is applied this rib is located immediately within the wall of the mouth 7 of the bottle and resists lateral shifting of the bottle cap and undue strain upon the marginal flange 10 thereof.

The cap flange 10 is formed at diametrically opposite points with the tongues or extensions 15 extending in the plane of said flange and terminating in the inwardly turned reinforcing beads 16. Adjacent the bead 16 of each tongue, a horizontal slot 17 is cut in the tongue and terminates adjacent the opposite vertical edges thereof, thereby providing a relatively narrow section of metal 18 at each end of the slot. It will be obvious, therefore, that the structure of the tongue is materially weakened 100 contiguous to the bead 16.

When the bottle cap or closure above described is applied, the inner sides of the beads 16 on the several tongues 15 ride upon the face of the rim surrounding the bottle 105 mouth as the cap is forced downwardly until the sheet 12 on the compressible disc 10 seats tightly against the edge of the mouth wall. In this downward movement of the cap, the tongues 15 will yield outwardly in view of 110 the inherent resiliency of the sheet metal from their point of connection with the

rim 10 until the beads 16 are positioned below the shoulder 8, when the said tongues will spring inwardly to their normal positions, the beads 16 fitting snugly against the face of said shoulder. Thus it will be apparent that the cap or closure is securely retained in its applied position against shifting movement or possible accidental detachment. It is important in those cases where the purity of the contents of the bottle or receptacle is guaranteed by the manufacturer that it should be impossible to remove the cap or closure without detection, whereby the purchaser can be assured that he is obtaining the original unaltered product. My present invention provides such means for insuring the immediate detection of the removal of the cap or closure. Thus, if the attempt is made to release the clamping or holding tongues, upon pulling or prying outwardly on the beads 16, the narrow weak sections of the metal 18 at opposite ends of the slot 17 will immediately yield since the bead is relatively stiff or rigid. Thus these narrow metal portions will be broken in the removal of the clamping tongues and it will be impossible to replace the tongues in their original condition so that the cap or closure could be again applied to the bottle without immediate detection that it had been removed since the bottle was originally sealed.

In Figures 3 and 4 of the drawings I have illustrated another form of the device in which the clamping or gripping tongues on the bottle cap are not provided with the slots 17. In this case, therefore, the lower ends of the tongues having the ribs 16 will not be broken off when the attempt is made to remove the bottle cap. However, an indicating means is provided in the form of an annular or circular sheet of light soft metal 19 such as tinfoil. The bottle cap at the juncture of its rim and body portion has an annular inclined or beveled section to which the edge 20 of the metal sheet 19 is permanently and securely fixed in any suitable manner. This sheet of soft metal is in close contact with the rim 10 and the tongues 15 of the bottle cap and is of greater width than the bottle cap so as to provide an annular skirt portion 21 extending downwardly below the tongues and preferably in engagement at its lower edge upon the body wall 55 of the bottle. Thus access to the tongues 15 is prevented and in order to engage the ribs 16 on said tongues with the fingers for the purpose of removing the bottle cap, it is first necessary to tear away the skirt portion 21 of the soft metal band or sheet 19. Obviously, when this metal band is thus torn or mutilated, it cannot subsequently be again restored to its original condition. Thus the purchaser will immediately observe that since the original contents was placed

in the bottle by the manufacturer, said bottle had been opened by the removal of the closure cap.

From the foregoing description considered in connection with the accompanying drawing, the construction, manner of operation and several advantages of my invention will be clearly and fully understood. It will be seen that the device herein described is very effective for the purpose in view, and as the bottle caps can be readily produced in large quantities by a simple stamping operation the article may be manufactured at small cost. I have herein disclosed several forms of the device which I have found to be very satisfactory in practical use but it will nevertheless be understood that the improved bottle closure might also be produced in various other alternative forms and I, therefore, reserve the privilege of resorting to all such legitimate changes in the form, construction and relative arrangement of the several parts as may be fairly embodied within the spirit and scope of the invention as claimed.

In Figure 6 of the drawing I have illustrated a closure cap produced from comparatively non-resilient metal having the tongues 15' initially extending outwardly at an angle from the edge of the marginal flange 10'. Thus it will be understood that after the cap has been applied over the mouth of the bottle or jar, suitable means is employed to bend or force the tongues 15' inwardly so that they will extend in the plane of the marginal flange 10', and thereby position the beads 16' on the free ends of said tongues beneath the annular shoulder on the neck wall of the vessel or container.

I claim:

1. A closure for receptacles comprising a cap adapted to be fitted over the mouth of the receptacle and having integral clamping devices for engagement with a shoulder on the receptacle wall, said cap being also provided with sealing means for the clamping devices comprising an annular skirt of soft metal secured to the upper edge of the cap fitting the circumferential portion of the cap and extending over said clamping devices to prevent the unauthorized removal of the cap by manipulation of said clamping devices.

2. A closure for receptacles comprising a cap adapted to be fitted over the mouth of the receptacle and having an annular rim portion provided with resilient tongues each having a gripping element on its free end for engagement with an annular shoulder on the receptacle wall, each of the tongues being provided with relatively weakened portions adjacent to the gripping element and beyond the confines of the cap whereby the gripping elements at such weakened por-

tions will break off from the lower end of the tongue upon the attempt to disengage the gripping elements from said shoulder in the removal of the cap from the bottle, and thereafter the remaining portion of the tongues are adapted to yieldingly engage the receptacle for removably holding the cap thereon.

3. A closure for receptacles comprising a cap adapted to be fitted over the mouth of the receptacle, said cap having an annular rim provided with a plurality of extending resilient tongues each terminating in a gripping element adapted for engagement with a shoulder on the receptacle wall, each tongue having a slot cut therein beyond the confines of the cap in parallel relation to

the gripping element and providing relatively weakened portions in the tongue at the opposite ends of said slot, whereby the gripping elements at such weakened portions of the tongue will yield and break off from the lower end of the tongue upon the attempted disengagement of the gripping elements from said shoulder to effect the removal of the bottle cap and thereafter the remaining portion of the tongues are adapted to yieldingly engage the receptacle for removably holding the cap thereon.

In testimony that I claim the foregoing as my invention, I have signed my name hereunder.

ROBERT SORGAN.
